PORATION OF PENNSYLVANIA.

SWITCH MECHANISM.

Application filed March 24, 1921. Serial No. 455,218.

Our invention relates to switch mechanism and particularly to enclosed switch mechanism of the safety type.

One object of our invention is to provide 5 an enclosed switch mechanism wherein separate covers are provided for preventing access to the switch elements and to the fuse elements and wherein both covers are so interlocked with the switch that they are 10 locked in closed position so long as the switch is in closed position.

Another object of our invention is to provide a switch mechanism, having the above characteristics, wherein the switch is held 15 in open position so long as the cover is in open position.

A further object of our invention is to provide a switch mechanism of the enclosed type wherein the terminals are connected to 20 the switch mechanism by means of a detachable plug or connector and wherein the connector is so interlocked with the switch mechanism that it cannot be disconnected therefrom so long as the switch is in closed 25 position, and wherein means are provided for preventing the attachment of the plug while the switch is in closed position.

Another object of the invention is to provide 30 a housing for a switch mechanism for heavy currents and which may be constructed of cast metal and which is substantial in every detail, weather proof and practical for application in mines, on portable apparatus and other installations in which the 35 apparatus will be subjected to rough usage and to operation by unexperienced attendants.

These and other objects, that will be made 40 apparent throughout the further description of the invention, are attained by means of the switch mechanism hereinafter described and illustrated in the accompanying drawings, wherein:

Figure 1 is a front view of the switch 45 mechanism;

Fig. 2 is an elevational view of one side of the mechanism shown in Fig. 1;

Fig. 3 is a sectional view of a fragment of the apparatus, taken on the line III—III of 50 Fig. 1, looking in the direction of the arrows; and

Fig. 4 is a sectional view of a fragment of

the apparatus, taken on the line IV—IV of Fig. 1, looking in the direction of the arrows.

55

Referring to the drawings, the apparatus includes a cast-metal housing 5 which is divided into two sections 6 and 7 by means of a transverse ridge 8. The section 6 contains a switch mechanism to be hereinafter described and is provided with a cover 9 which is hinged to a side of the housing 5 by means of the hinge 11. This cover is provided with slotted lugs 12 that are disposed on opposite sides of the cover and are adapted to receive the free ends of eye bolts 13 that are pivoted, by means of rivets 14, to integral lugs 15 on the sides of the housing 5. The lid is clamped in closed position by means of wing nuts 16 mounted on the threaded 70 ends of the eye bolts 13.

The section 7 contains fuse mechanism to be hereinafter described and is provided with a cover 17 that is hinged to one end of the housing 5 by means of a hinge 18. This 75 cover is provided with lugs 12, similar in every respect to those on the cover 9, and is clamped to the housing by eye bolts 13 in a manner similar to that in which the cover 9 is clamped.

An insulating panel 18 is secured to the bottom of the housing upon which the switch and fuse mechanism is mounted. The switch mechanism is of the three-pole type for use in a three-wire system and includes three 85 switch-jaw members 19 to which switch-blade members 21 are pivotally attached. Three switch-jaw members 22 are disposed upon the panel and opposite the pivot-jaw members 19 and are adapted to receive the 90 switch-blade members 21. The line terminals 23 are connected to the switch-jaw members 22.

The portion of the panel disposed beneath the cover 17 is provided with three pairs of fuse-jaw members 24 that are adapted to receive the knife-blade terminals of the fuses 25. Conductors 26 connect the pivot-jaw members 19 with the adjacent fuse-jaw terminals 24 and the load-line terminals 27 are connected to the other fuse-jaw terminals 24. The load terminals terminate at 28 in a receptacle that is mounted on one end of the housing 5 and is adapted to receive a 95 100

connector plug 31 to which the flexible cable 32, containing the load conductors is attached.

The line terminals from the cable conduit 5 terminate in a connection box 33 that is detachably secured to the housing 5 by means of bolts 34. It will be seen from the foregoing that the circuit through the box is from the line terminals 23 through the 10 switch-blade members 21, the fuse members 25 and the load terminals 27, and that, when the switch members 21 are in open position, the fuses 25 are disconnected from the circuit and may be inspected or changed without 15 danger or injury.

In order to insure that the fuses shall be inaccessible while the switch is in closed position, interlocking means, to be herein-after described, is provided between the 20 switch and the covers closing the housing. As this switch mechanism is particularly adapted for use in circuits carrying heavy currents, and as, in mine work, where circuit-opening contacts should be totally 25 closed to prevent explosion of mine gases, it is desirable, as a matter of absolute protection, that the connector plug 31 may not be disconnected from the receptacle 29 so long as current is passing through the circuit. 30 Interlocking means is, therefore, provided between the switch and the connector plug whereby the plug is retained in operative current-conducting engagement with the receptacle so long as the switch remains in 35 closed position. As a further precaution, the interlocking means is made of such a nature that the plug 31 cannot be attached to the receptacle for the purpose of completing the circuit unless the switch is in open 40 position.

The interlocking mechanism for the cover closing the switch compartment, the cover for closing the fuse compartment and the connector plug will be described in the order named. The switch-blade members 21 are connected at their free ends, by means of an insulating bar 35, and the switch is operated by means of an operating lever 36 that is pivoted to the side of the housing 5 within 45 a bearing 37. The operating lever 36 is provided with two extensions 38 that operatively engage the insulating bar 35. The lever 36 is also provided with an operating shaft 39 which extends through the bearing 37 and is provided with an operating handle 41 by means of which the switch lever 36 may be turned in order to move the switch-blade members to open and to closed 55 positions.

60 The lever 36 is provided adjacent the shaft 39 with an arcuate cam 42, (see Figs. 2 and 3), the inner surface 43 of which is concentric to the axis of rotation of the lever or to the center of the shaft 39. The free 65 end of the cover 9 is provided with an in-

tegral inwardly projecting lug 44 that is provided, at one corner of its extremity, with a cylindrical boss or projection 45 which engages the inner surface 43 of the cam 42 when the switch lever 36 is in closed 70 position.

Opening movement of the cover 9 is prevented by the engagement of the boss 45 with the cam. When the lever 36 is moved to open position, the cam 42 is so moved 75 that the end thereof clears the boss 45 and permits the cover to be moved to open position. It will be seen from the foregoing that, so long as the switch is in closed position, the cover cannot be opened. 80

In order to prevent the closing of the switch while the cover is open, an interlocking means is provided which consists of a floating plate 47 that is provided with two fixed rods 48 and 49 which extend outwardly from the plate 47. A stationary rod 51 is riveted, at its inner end, to the bottom of the housing 5 and serves as a centering guide for the movement of the floating plate 47. The rods 49 and 48 prevent rotation of 90 the plate about the rod 51.

The upper end of the rod 51 is supported in a bracket 52 cast integral with the side of the housing 5. This bracket is provided with a perforation 53 through which the 95 rod 49 extends and with a perforation 54 through which the rod 48 projects. The lever 36, adjacent the shaft 39, is provided with an opening 55 which is adapted to register with the opening 53 in the bracket, 100 when the operating lever 36 is in open position.

A spring 56, that is disposed between the bottom of the housing and the floating plate 47, forces the plate 47 outwardly to move 105 the rod 49 into the opening 55 and thereby prevent rotary movement of the operating lever 36. Outward movement of the floating plate 47 is only possible when the cover 9 is open, for the reason that the lug 44 engages the upper end of the rod 48 and depresses the plate 47. When the cover 9 is open, the plate 47 is free to move outwardly and will do so when the opening 55 registers with the opening 52. The lever 36 is 110 then locked in open position and cannot be moved until the cover 9 is moved such distance that the lug 44 may engage the rod 48 and move the rod 49 out of the opening 55 in the lever 36. It will be evident from the 115 foregoing that the final closing movement of the cover releases the operating lever so that it may be turned to closed position.

The interlocking means for the cover 120 comprises a bell-crank lever 57 that is pivoted to the end of the housing 5 by means of a bolt 58 in such a manner that it turns about an axis perpendicular to the base of the housing. The lever is provided with an arm 59 that is disposed across the path of move- 125 130

ment of the lug 61 that is a continuation of a portion of the cover hinge. The lever 57 is pivotally connected to the operating handle 41 by means of a connecting rod 62.

5 When the switch is moved to open position, the bell-crank lever 51 is rotated to move the arm 59 out of the path of movement of the lug 61. The cover 17 may, at this time, be opened. It will be seen from the 10 foregoing that the cover cannot be opened so long as the switch is in closed position.

When the cover 17 is open, the lug 61 rotates about the hinge 18 in such a manner as to prevent the arm 59 from rotating to 15 closed position, thus preventing closing of the handle 41 until after the fuse compartment door 17 has been closed.

In order to prevent the attachment or detachment of the plug connector 31 when the 20 switch is in closed position, a yoke 63, which straddles the conductor 31 and operates in an annular groove 64 thereof, is mounted for reciprocation on the bracket 65 that is an integral part of the housing. The outer end 25 of the yoke 63 is pivotally connected to the arm 66 of the bell-crank lever 57 and is withdrawn thereby a sufficient distance to clear the plug connector 31 when the switch handle 41 has been moved to open position. The 30 arm 66 is provided with a slot 67 in which the pivot pin 68 operates. It will be seen from the foregoing that, when the switch is in closed position, the plug connector cannot be attached, or, if it is attached, it cannot 35 not be disengaged.

While we have described the housing structure as being made of cast metal, it is obvious that the housing may be constructed of sheet metal and that the various brackets and 40 projecting portions thereof may be separate from the main body of the housing and se-

cured thereto by any desired fastening means. Constructed as illustrated and described, the mechanism is rigid and is positive in its action.

45 While we have described and illustrated but one embodiment of our invention, it will be apparent to those skilled in the art that various changes, modifications, substitutions, additions and omissions may be made in 50 the apparatus illustrated without departing from the spirit and scope of the invention, as set forth in the appended claims.

55 We claim as our invention:

1. Switch mechanism comprising a housing having a switch member within the housing, a fuse member within the housing, separate covers for closing access to the switch member and to the fuse member, a connector for operatively connecting a conductor to the 60 said members, means for operating the switch member and means actuated thereby for locking the cover members in closed position and the connector in operative relation to the said members so long as the switch 65 is in closed position.

2. Switch mechanism comprising a housing, a switch member within the housing, a fuse member within the housing, separate covers for closing access to the switch member and to the fuse member, the said covers being hinged thereto on hinges disposed at 70 right angles to one another, and means interlocking the covers with the switch whereby by opening movement of the covers is precluded so long as the switch is in closed position.

75 In testimony whereof, we have hereunto subscribed our names this 18th day of March, 1921.
